WEAVING DEVICE

Albert B. Collingbourne, Elgin, Ill.

Application October 21, 1935, Serial No. 45,853

5 Claims. (Cl. 139—34)

This invention relates to weaving devices, particularly to weaving devices comprising a plurality of identical pieces adapted to be assembled to form an adjustable frame. The several pieces 5 may be assembled in desired relationship for weaving purposes without the aid of fastening devices. The teeth for holding the warp and woof threads are relatively small and close together so as to permit either fine or coarse fabrics 10 to be woven thereon by using all of the teeth or alternate teeth.

In the drawing:

Fig. 1 is a plan view of a weaving device embodying my invention.

Fig. 2 is a vertical sectional view taken on the line 2—2 of Fig. 1.

Fig. 3 is a side elevation of one of the identical pieces which form the weaving device.

In that embodiment of the invention shown in 20 the drawing, 10, 11, 12 and 13 indicate identical bars of wood or other suitable material, each preferably twice as deep as it is wide, and of any desired length. The upper surface of each bar is provided with integral, uniformly spaced, upwardly projecting teeth 14, which are substantially equal in width to the spaces between them when viewed as in Fig. 3. Preferably there are 25 four teeth to each inch or seven to each two inches.

30 Adjacent one end of each bar is a deep open top notch 15 extending downwardly from the upper surface, and having flat side walls 16, 16, transversely of the bar. On its lower surface, each bar is provided with a plurality of open 35 bottom, flat sided notches 17, spaced apart according to the degree of adjustability desired. The depth of the side walls 18, 18 of the notches 17 is approximately equal to the depth of the part 19 of the bar beneath the notch 15, and the depth 40 of the side walls 16 of the notch 15 is approximately equal to that portion of the bar and teeth above the notches 17.

To assemble the weaving device, the bar 10 is 45 placed at an angle to the bar 11 and across it, so that the deep notch 15 of the piece 10 and one of the shallow notches 17 of the piece 11 register, and the floor 20 of notch 15 in bar 10 and ceiling 21 of notch 17 of bar 11 are in contact with each 50 other, and the sides of the bar 11 above the notch 17 are frictionally engaged by the walls 16 of the notch 15 in the bar 10. The other bars required to form a rectangular frame are similarly connected and thus the teeth 14 of the several pieces are all in one horizontal plane.

The bars 10, 11, 12 and 13 may be assembled to form square or oblong weaving frames. Thread may be wound on teeth 14 from bar 13 to 11 and from 12 to 10 and then the crossed threads may be tied together. Warp threads 5 may also be wound on the teeth of bars 12 and 10, and woof threads may be woven across the warp threads in a familiar manner.

Changes may be made in details of construction without departing from the scope of my invention 10 and I do not intend to be limited to the exact form shown and described, except as set forth in the appended claims.

I claim:—

1. A weaving device comprising a plurality of 15 identical pieces assembled in the form of a frame and held together by frictional engagement, each piece being of uniform width and having a plurality of uniformly spaced teeth projecting from its top, a deep notch extending downwardly from the top of the piece near one end of each piece, and a plurality of open bottom notches in the bottom of each piece, the side walls of the deep notch of one piece extending upwardly and engaging the side surfaces above one of the open bottom 20 notches of another piece.

2. A weaving device comprising a plurality of 25 identical pieces assembled in the form of a frame and held together by frictional engagement, each piece being of uniform width and having a plurality of uniformly spaced teeth projecting from its top, the teeth being of a width substantially 30 equal to the width of the spaces between them, a deep notch extending downwardly from the top 35 of the piece near one end of each piece, and a plurality of open bottom notches in the bottom of each piece, the side walls of the deep notch of one piece extending upwardly and engaging the side surfaces above one of the open bottom 40 notches of another piece.

3. A weaving device comprising a plurality of 45 identical pieces assembled in the form of a frame and held together by frictional engagement, each piece being of uniform width and having a plurality of uniformly spaced teeth projecting from its top, approximately seven teeth to each two 50 inches, a deep notch extending downwardly from the top of the piece near one end of each piece, and a plurality of open bottom notches in the bottom of each piece, the side walls of the deep notch of one piece extending upwardly and engaging the side surfaces above one of the open bottom 55 notches of another piece.

4. A weaving device comprising a plurality of identical pieces assembled in the form of a frame and held together by frictional engagement, each piece being of uniform width and having a plurality of integral, uniformly spaced teeth projecting from its top, a deep notch extending downwardly from the top of the piece near one end of each piece, and a plurality of open bottom notches in the bottom of each piece, the side walls of the deep notch of one piece extending upwardly and engaging the side surfaces above one of the open bottom notches of another piece.
5. A weaving device comprising a plurality of

identical pieces assembled in the form of a frame and held together by frictional engagement, each piece being of uniform width and having a plurality of uniformly spaced teeth projecting from its top, an open top notch extending downwardly from the top of the piece near one end of each piece, and a plurality of open bottom notches in the bottom of each piece, the side walls of the open top notch of one piece extending upwardly and engaging the side surfaces above one of the open bottom notches of another piece. 5

ALBERT B. COLLINGBOURNE.
